Inventor: Joseph G. Kuhlman,
By Thomas G. Orrig, Atty.

UNITED STATES PATENT OFFICE.

JOSEPH FREDERICK KUHLMAN, OF ANAMOSA, IOWA.

WASHING-MACHINE.

SPECIFICATION forming part of Letters Patent No. 378,138, dated February 21, 1883.

Application filed February 14, 1887. Serial No. 227,623. (No model.)

To all whom it may concern:

Be it known that I, JOSEPH FREDERICK KUHLMAN, a citizen of the United States of America, and a resident of Anamosa, in the 5 county of Jones and State of Iowa, have invented an Improved Washing-Machine, of which the following is a specification.

My object is to facilitate the washing of clothing in a tub of water; and my invention consists in the construction and combination of a cylinder having a wash-board surface partially composed of coiled metal springs and a flexible wash-board and a tension device with a portable frame adapted to rest on top of a common tub, as hereinafter set forth, pointed out in my claims, and illustrated in the accompanying drawings, in which—

Figure 1 is a side view, and Fig. 2 a top view, of my machine; and Fig. 3 is a vertical 20 transverse section through the dotted line *x x* of Fig. 2.

A are the wooden sides, and *B* the cross-pieces, of a rectangular frame adapted to be placed over a common wash-tub, as indicated 25 in Fig. 3.

C is a wooden cylinder provided with gudgeons or journals at its ends and a wash-board surface on its periphery, composed of a series 30 of fluted wooden bars, *d*, that are nailed flat upon the cylinder, as clearly shown in Fig. 3, and in such a manner that coiled spring-wires *f* can be placed between them, and also fastened securely to the cylinder by means of staples, or in any suitable way, so that each 35 coiled wire produces series of elastic ribs that are in right-angled positions relative to the ribs of the fluted bars *d*.

g is a frame fitted in corresponding slots formed in the sides *A* in such a manner that 40 it will slide horizontally. It is provided with sliding bearings *g'*, that admit the journals on the ends of the cylinder and allow the cylinder to be moved horizontally with said sliding bearings. Coiled springs *h*, connected with 45 the frame *g*, and the fixed cross-pieces *B* serve as a tension device in adjusting the sliding frame and roller relative to a wash-board surface, against which the cylinder will press and rub articles to be washed, and, as required to 50 beself-adjusting relative to articles of different size and bulk, the springs *h* are secured by

means of pins *h'*, fixed to the wood, or in any suitable way.

m m are cross-pieces fixed to the tops and bottoms of the side pieces, *A*, to support my 55 flexible wash-board in vertical position. A series of coiled wire springs, 1 2 3 4, are independently fastened at their ends to the cross-pieces *m* by means of staples, or in any suitable way, in such a manner that they will be 60 in contiguous and parallel positions, and also in such a manner that each spring and each coil in each spring will be allowed independent motion relative to any article or button on an article of clothing that may be pressed thereon 65 by means of the cylinder.

n represents a wringer-support fixed on top of the sides *A* of the frame.

r is a shelf adapted to retain soap.

s is a bar fitted in slots in the sides *A* in such 70 a manner that it can slide to and from the wash-board, composed of the series of springs 1 2 3 4, to serve as a tension device for regulating the resistance of the springs relative to pressure produced by articles pressed thereon by the 75 cylinder when it is rotated by means of a crank-handle on its end. Coiled springs *h*, corresponding with those that press the roller toward the vertical wash-board, are connected 80 with the bar *s* and the cross-piece *B*.

In the practical use of my machine I place it over a tub of water, and then place articles to be washed in the water and in succession lift them out and place them upon the cylinder, and then rotate the cylinder in reverse ways 85 to press and rub all parts of the fabric against the flexible wash-board, that extends vertically at the side of the cylinder.

I am aware that a wash-board has been made of coiled springs in such a manner that they 90 produced a concave surface or basket adapted to retain articles suspended under a roller. I am also aware that rubber tubes have been fixed on the corrugated surface of a cylinder; but my manner of combining coiled springs 95 with a cylinder to produce a wash-board surface and with a frame to produce a vertical and flexible wash-board at the side of the cylinder is novel and greatly advantageous in that each spring and each coil acts independently upon 100 the fabric that is pressed and rubbed between the cylinder and flexible wash-board, and the

clothing that is pressed against the series of parallel and vertically-extending series of springs 1 2 3 4 is elevated out of the water and drained at every revolution of the cylinder 5 and at the same time it is pressed and rubbed.

I claim as my invention—

1. In a cylinder for washing-machines, the combination of coiled springs with fluted bars or sections of corrugated surface to produce a 10 series of ribs that project at right angles to the bars or corrugations, for the purposes set forth.
2. An improved washing-machine comprising a portable frame, A B, a rotating cylinder,

C, in a sliding frame, g g', a series of coiled springs, 1 2 3 4, fixed to cross-pieces m, a sliding bar, s, and springs h, for pressing the cylinder C and the bar s toward the flexible wash-board, composed of the said series of springs 1 2 3 4, arranged and combined substantially as shown and described, to operate in the manner set forth. 15 20

JOSEPH FREDERICK KUHLMAN.
